UNITED STATES PATENT OFFICE.

LESTER KIRSCHBRAUN, OF CHICAGO, ILLINOIS.

WATERPROOF AND GREASEPROOF PAPER.

No Drawing. Application filed August 16, 1922, Serial No. 582,315. Renewed April 30, 1925.

To all whom it may concern:

Be it known that I, LESTER KIRSCHBRAUN, a citizen of the United States, residing in the city of Chicago, county of Cook, and State 5 of Illinois, have invented certain new and useful Improvements in Waterproof and Greaseproof Paper, of which the following is a specification.

This invention relates to improvements in 10 waterproof and greaseproof paper and process of making same, and refers more particularly to paper made from a mixture of fibrous stock and a specially prepared bituminous emulsion. In its broader aspects 15 the specially prepared emulsion, instead of being used with fibrous stock, may be itself used as a paste.

The invention may be carried out as follows: To a bituminous emulsion prepared 20 as described in my issued Patent, U. S. No. 1,417,835, I add a quantity of concentrated sulphite liquor. The sulphite liquor and bituminous emulsion are miscible in all proportions, or during the production of the 25 bituminous emulsion I may add to the clay which is used as the emulsifying agent, a quantity of concentrated sulphite of liquor, which combined with the clay, acts as an emulsifying agent, the process being carried 30 on as described in said issued patent. When the sulphite liquor, is used, with the clay as an emulsifying agent, it may be noted that the resulting emulsion has a very brown color which is characteristic of this particu- 35 lar operation.

The emulsion prepared as above described, may be added to paper stock in the beaters and subsequently treated after thorough mixing with formaldehyde, the result of which 40 is to coagulate the sulphite liquor, converting it into such form that it is not affected by grease.

The stock so prepared may be further treated with alum and then run over a 45 paper machine in the usual manner. When subjecting this to the drying action of the paper machine, the bituminous material

coalesces and the transformation of the colloidal matter of the sulphite liquor into a greaseproof form is thereby accomplished. 50 The resulting product of this treatment is a paper containing the bituminous material as a waterproofing agent in addition to the grease proofing effects imparted by the sulphite liquor. 55

The same emulsion may be applied by coating previously prepared paper and applying together in such a form that the film of the waterproof and greaseproof composition is interposed between the plies. 60

An invention may be carried out in which the colloidal clay is dispensed with and the sulphite liquor alone used with an emulsifying agent. The method of making this emulsion may be, in all essential particulars, 65 similar to the method employed when using clay alone.

I claim as my invention:

1. A paper consisting of fibrous web, bituminous material and the conversion product of sulphite liquor and formaldehyde. 70

2. A paper consisting of a fibrous web, fusible waterproofing material, and a greaseproofing conversion product of sulphite liquor. 75

3. A waterproof fibrous composition, comprising fibrous stock having incorporated therewith a bituminous material dispersed in an aqueous vehicle with sulphite liquor. 80

4. A waterproof and greaseproof fibrous composition, comprising fibrous stock having incorporated therewith a bituminous material dispersed in an aqueous vehicle with sulphite liquor, the composition having been rendered greaseproof by the addition of formaldehyde to the sulphite liquor. 85

5. A waterproof and greaseproof fibrous composition, comprising fibrous plies having interposed between certain plies a bituminous material dispersed in an aqueous vehicle and rendered greaseproof by the addition of the conversion product of sulphite liquor. 90

LESTER KIRSCHBRAUN.
